(57) **CLAIM**

The ornamental design for a rifle brake, as shown.

DESCRIPTION

FIG. 1 is an upper perspective view of a rifle brake according to the present invention.

FIG. 2 is a front view of the rifle brake in FIG. 1.

FIG. 3 is a right side view of the rifle brake in FIG. 1.

FIG. 4 is a left side view of the rifle brake in FIG. 1.

FIG. 5 is a back view of the rifle brake in FIG. 1.

FIG. 6 is a top view of the rifle brake in FIG. 1; and,

FIG. 7 is a bottom view of the rifle brake in FIG. 1.

The broken lines in FIG. 3 are included for the purpose of illustrating a portion of the claimed design that forms no part of the claimed design.
